(57) **CLAIM**

The ornamental design for a display screen or portion thereof with an animated graphical user interface, as shown and described.

DESCRIPTION

A portion of the disclosure of this patent document contains material to which a claim for copyright and/or trademark is made. The copyright and/or trademark owner has no objection to the reproduction of the patent document or the patent disclosure, as it appears in the U.S. Patent and Trademark Office records, but reserves all other copyright and/or trademark rights whatsoever.

U.S. design patent application Ser. No. 29/569,717, filed Jun. 29, 2016, titled “Display Screen or Portion Thereof With a Computer Icon,” is hereby incorporated by reference herein in its entirety.

FIG. 1 is a front view of a display screen or portion thereof with an animated graphical user interface showing a first image of a sequence showing our new design;

FIG. 2 is a second image thereof;

FIG. 3 is a third image thereof; and,

FIG. 4 is a fourth image thereof.

The outer perimeter shown in broken lines in the figures illustrates a display screen or portion thereof, and forms no part of the claimed design. The remaining broken lines in the figures illustrate portions of the animated graphical user interface that form no part of the claimed design.

The appearance of the image transitions sequentially between the images shown in FIGS. 1-4. The process or period in which an image transitions to another forms no part of the claimed design.

The stipple shading in FIGS. 3 and 4 indicates a contrast in appearance.
